Primary Examiner — Keli L Hill*Assistant Examiner* — Harold E Blackwell, II(74) *Attorney, Agent, or Firm* — Eric Kelly(57) **CLAIM**

What is claimed is the ornamental design for a lighting junction box, as shown and described.

DESCRIPTION

FIG. 1 illustrates a top perspective view of a new and ornamental lighting junction box;

FIG. 2 illustrates a front view thereof;

FIG. 3 illustrates a rear view thereof;

FIG. 4 illustrates a right-side view thereof;

FIG. 5 illustrates a left-side view thereof;

FIG. 6 illustrates a top view thereof;

FIG. 7 illustrates a bottom view thereof; and,

FIG. 8 illustrates a bottom perspective view thereof. Broken lines in the drawings depict portions of the lighting junction box that form no part of the claimed design.
